US0D1067771S

(12) **United States Design Patent** (10) Patent No.: **US D1,067,771 S**
Merlin et al. (45) Date of Patent: ** Mar. 25, 2025

(54) **BOTTLE STOPPER**

(71) Applicant: **Monkey Business Design Israel 2021 Ltd**, Ramot Hashavim (IL)

(72) Inventors: **Sharona Merlin**, Tel-Aviv Jaffa (IL); **Chen Ben-Ami**, Tel-Aviv Jaffa (IL)

(73) Assignee: **Monkey Business Design Israel 2021 Ltd**, Ramot Hashavim (IL)

(**) Term: **15 Years**

(21) Appl. No.: **35/519,375**

(22) Filed: **Nov. 23, 2023**

(80) **Hague Agreement Data**

Int. Filing Date: **Nov. 23, 2023**

Int. Reg. No.: **DM/233642**

Int. Reg. Date: **Nov. 23, 2023**

Int. Reg. Pub. Date: **Dec. 15, 2023**

(30) **Foreign Application Priority Data**

Jun. 26, 2023 (EM) 015025989-0001

(51) **LOC (15) Cl.** **07-06**

(52) **U.S. Cl.**

USPC **D9/441**; D9/632

(58) **Field of Classification Search**

USPC D9/600, 631, 632, 434, 435, 439, 441, D9/451, 499
